UNITED STATES PATENT OFFICE

2,044,447

ELEVATOR CONTROL DEVICE

Joseph Rice, Chicago, Ill., assignor of one-half to
 Elevator Company of America, Chicago, Ill., a
 corporation of Illinois

Original application January 13, 1930, Serial No.
 420,611. Divided and this application March
 21, 1934, Serial No. 716,600

5 Claims. (Cl. 254—186)

My invention relates to elevator control devices and more particularly to a drive mechanism for elevators and the like wherein the principal purpose of the invention is to improve the control 5 in the operation of the drive mechanism for the elevator particularly in changes of speed of the elevator by the employment of an inertia controlling device.

This application is a division of my application 10 Serial No. 420,611, filed January 13, 1930.

It is also a purpose of this invention to provide in combination with the cable drum for driving an elevator of an auxiliary braking device co-operating with the motor drive braking device to 15 create a drag on the machine and to assist the slowing of an elevator at a stop.

Other objects and advantages of the invention will appear as the description proceeds in connection with the accompanying drawing where- 20 in—

Fig. 1 is a side view showing the cable drum of an elevator in combination with my improved control device;

Fig. 2 is a section on the line 2—2 of Fig. 1;

Fig. 3 is a reduced side view taken from the line 3—3 of Fig. 1.

Referring now in detail to the drawing, I show at 5 the usual cable sheave or drum over which the cables moving the elevator cars up and down 30 the shaft operate. This drum is mounted on a suitable frame consisting of the base 6, standards 7 and 8, bearings 9 and 10, and drum shaft 11. The shaft is driven from a suitable power device such as the motor 12, the shaft of which connects by means of worm and worm gear drive indicated at 13 to the shaft 11 on which the drum is mounted. The shaft 14 of the drive motor is provided with the usual braking drum 15 and brake shoes 16 for applying a braking effect to 40 this shaft in stopping the elevator.

Braking in this fashion, however, subjects the drive shaft of the motor and the worm and gear drive to a terrific strain owing to the inertia of the cable drum and the car, so I have provided in addition to this braking device an auxiliary braking device which is particularly effective in bringing the car to a stop. This auxiliary braking device consists of an inertia controlling member comprising an auxiliary brake drum 17 mounted 50 on a suitable shaft 18 carried in the standard 7 and auxiliary standard 19 suitable bearings being provided. The drum 17 has associated therewith the brake shoes 20 and 21 which are controlled by a small electric motor 22 through suitable gear mechanism, the details of which are

well known and form no part of the present invention. This auxiliary shaft 18 then is connected by means of the large gear 23 and pinion 24 to the main drum shaft 11 so as to rotate the auxiliary shaft 18 at a materially reduced speed 5 from the drum shaft 11.

This in itself creates a drag at all times on the drum shaft which tends to avoid overrunning by the elevator and which also tends to slow down the elevator when the power is cut off 10 from the drive motor and the brake applied to its shaft thus avoiding a certain amount of backlash which would occur if the inertia of the drum and elevator were not retarded in some fashion.

The brake shoes 21 when applied to the drum 15 15 effect a powerful braking action on the drum shaft since their action on the slow moving drum 17 is communicated through the reduction gearing directly to the main drum shaft and give a smoother and greater braking power than would 20 be obtained if these brake shoes were applied directly to the drum itself. This is because the drag of the slow speed gear 23 tends to brake the drum, and the slow speed of the brake drum and gear 23 tend to offset the momentum of the drum 25 shaft. The force on the brake drum during a single revolution plus the friction losses in transmission is reduced in accordance with the gear ratio between gears 23 and 24 but the reduced force and friction loss is applied over a number 30 of revolutions of the drum shaft. So for each turn of the brake drum the braking action is applied through several turns of the drum shaft.

This auxiliary braking device is found to be 35 practically effective on push button type of elevators where the control of the braking is all automatic. Also the combination of the brake on the high speed shaft of the driving motor with the auxiliary braking device applied on a drum rotating at a much lower speed than that of the 40 cable shaft gives an ideal combination in that we have braking effects applied to both a rotating element going faster than the cable shaft and a rotating element going slower than the cable shaft.

From the above description, it is thought that the construction and advantages of this device will be clear to those skilled in this art.

Having thus described my invention, what I 50 claim as new and desire to secure by Letters Patent is:

1. An elevator drive mechanism including a drum shaft having a cable drum thereon, a higher speed shaft connected to said drum shaft, a lower speed shaft connected to said drum shaft, 55

- and braking means on the higher and lower speed shafts said lower speed shaft being driven at a speed substantially less than the speed of said drum shaft.
5. 2. An elevator drive mechanism including a drum shaft having a cable drum thereon, a higher speed shaft connected to said drum shaft, a lower speed shaft connected to said drum shaft, and braking means on the higher and lower speed shafts one of the two last mentioned shafts driving the drum shaft and the other being driven therefrom.
10. 3. An elevator drive mechanism including a drum shaft having a cable drum thereon, a higher speed shaft connected to said drum shaft, a lower speed shaft positively connected to said drum shaft, and a drum fixed on said lower speed shaft, said drum having a brake cooperating therewith whereby to stop said drum shaft said lower speed shaft being driven at a speed substantially less than the speed of said drum shaft.
15. 4. In an elevator power unit, a cable drum, a shaft upon which drum is fixed, a higher speed shaft connected to said first named shaft, power
- means for driving said higher speed shaft, a lower speed shaft, a reduction gearing positively connecting said lower speed shaft to the first named shaft to drive the lower speed shaft at a speed materially reduced from that of the first named shaft, and means on said lower speed shaft co-operating with said gearing to create a drag on said first named shaft at all times. 5
5. In an elevator power unit, a cable drum, a shaft upon which drum is fixed, a higher speed 10 shaft connected to said first named shaft, power means for driving said higher speed shaft, a lower speed shaft, a reduction gearing positively connecting said lower speed shaft to the first named shaft to drive the lower speed shaft at a speed 15 materially reduced from that of the first named shaft, and means on said lower speed shaft co-operating with said gearing to create a drag on said first named shaft at all times, said means comprising a brake drum on said lower speed 20 shaft, and brake shoes engageable with said brake drum to apply a braking force to the first named shaft through said gearing. 25
